CLAIM

The ornamental design for a wall mount as shown and described.

DESCRIPTION

FIG. 1 is a right, front-side perspective view of a wall-mount.

FIG. 2 is a left, rear-side perspective view thereof.

FIG. 3 is a front-side elevation view thereof.

FIG. 4 is a rear-side elevation view thereof.

FIG. 5 is a right-side elevation view thereof.

FIG. 6 is a left-side elevation view thereof.

FIG. 7 is a top plan view thereof.

FIG. 8 is a bottom plan view thereof.

FIG. 9 is a right, front-side perspective view of a wall mount according to a second embodiment.

FIG. 10 is a left, rear-side perspective view thereof.

FIG. 11 is a front-side elevation view thereof.

FIG. 12 is a rear-side elevation view thereof.

FIG. 13 is a right-side elevation view thereof.

FIG. 14 is a left-side elevation view thereof.

FIG. 15 is a top plan view thereof; and,

FIG. 16 is a bottom plan view thereof.

The broken lines shown represent portions of wall mount that form no part of the claimed design.
